UNITED STATES PATENT OFFICE.

GEORGE H. HEYS, OF LYNN, MASSACHUSETTS, ASSIGNEE TO UNITED SHOE MACHINERY CORPORATION, OF PATERSON, NEW JERSEY, A CORPORATION OF NEW JERSEY.

MACHINE FOR OPERATING ON FILLER PIECES FOR SHOES.

Application filed August 17, 1923. Serial No. 657,935.

The present invention relates to boots and shoes and in particular to the manufacture of fillers or filler pieces such as are used in certain types of shoes to provide an inside 5 tread surface adapted to conform to the more prominent projections and depressions of the sole of the foot to insure that the pressure caused by the weight of the body will be distributed uniformly over those parts of the 10 foot which should properly sustain it.

The use of fillers or filler pieces for this purpose is disclosed in United States Patent No. 1,120,489, to Matthew Hilgert, dated Dec. 8, 1914, in which there is described a process 15 of manufacturing shoes which can be practised on a large scale with the use of modern shoemaking machinery, and which is adapted to produce shoes that will fit the feet more accurately and will be more comfortable than 20 the usual factory-made shoes. In manufacturing filler pieces of the character referred to in said patent, it has been customary to make first a foot-shaped form or last of a desired foot size, the last having a bottom face 25 corresponding in surface contour to that of the sole of an average normal foot of said size. Next a filler piece blank having the desired marginal shape is made to conform in surface contour to that of the bottom face of 30 the foot last, either by applying the blank directly to the bottom of the foot last while the blank is in a moistened or tempered state and allowing it to remain upon the last until 35 dry, or by shaping the blank between a pair of molds one of which has the contour and dimensions of the bottom of the foot last and the other of which has the contour and dimensions of the bottom of a last upon which the shoe is to be made. The practice of this 40 method of making filler pieces necessarily requires the provision of a different foot last and a different filler piece die for each size, width and style of shoe to be manufactured. When production of shoes in any substantial 45 quantity is contemplated, molds are provided for shaping the filler pieces and a different pair of co-operating molds is required for each size, width and style of shoe to be made. The molds are costly and the manufacture of 50 the filler pieces, and consequently the manufacture of shoes provided therewith, has necessarily been expensive heretofore.

One object of the present invention is to

reduce the cost of manufacture of filler pieces of the above described general character and 55 to enable shoes provided with such filler pieces to be produced in quantity under the usual shoe factory conditions so that they may be sold at a more moderate price than has heretofore been possible.

In carrying out this object, advantage is 60 taken of the fact that such variations in the marginal contour of the filler pieces as are necessary to adapt them for use in shoes of different styles, occur principally in the toe 65 and forepart portions of the filler pieces, i. e., in those portions which are forward of the ball line. Advantage is also taken of the fact that variations over a large range of sizes at the heel ends of the filler pieces are small 70 and accordingly it is practicable to make filler pieces with rear portions having initially such marginal contour as is ultimately required for a number of different sizes and widths of shoes. It is practicable, also, to 75 make these filler pieces with foreparts having such form and dimensions as to allow for various changes of marginal contour such as may be required for use in shoes of widely 80 different styles and to adapt the filler pieces 85 for use in shoes of any particular style by subsequently shaping the margins of the foreparts of the filler pieces by trimming operations.

In accordance with one feature of the present invention, therefore, means has been provided for supporting a filler piece and relatively moving and guiding the filler piece and a stock trimming device to cause the latter to trim the toe and forepart of the filler piece 90 without trimming any of the remaining portions of the filler piece. The term "trim" as above used and as hereinafter employed in the appended claims is intended to include operations of any character whereby the final 95 shape of the filler piece is produced by the removal of stock from the partially completed article. Preferably the portion of the filler piece above referred to as the "forepart" or "toe and forepart" will include the entire 100 portion which is forward of the ball line while what has been above referred to as the rear portion of the filler piece will include the entire portion at the rear of the ball line.

Preferably also, and as illustrated, a sole 105 rounding machine is employed to perform the

shaping or trimming of the forepart of the 5 filler piece for the purpose of determining its ultimate marginal contour. In the rounding operation, the marginal contour of the forepart of the filler piece is determined, as herein 10 illustrated, by a pattern which is larger throughout its middle and rear portion than the corresponding shank and heel portion of the filler piece and is adapted to overlap said shank and heel portion to prevent cutting of 15 this part of the filler piece by the trimming knife, but which has a marginal contour at the forepart in accordance with the particular style of filter piece to be produced, so that it will guide the trimming knife in the usual manner during its trimming movement around said forepart. The provision of a 20 pattern shaped to guide a cutter around the forepart of a filler piece to trim the same and to prevent the cutter from trimming the rest of the filer piece is considered to be an important feature of the invention.

By the employment of the herein described apparatus whereby a filler piece is preliminarily 25 formed with its forepart shaped to allow for variations in style and is subsequently trimmed in accordance with the particular style desired, it will be obvious that only a comparatively small number of molds will be required in the manufacture of filler pieces 30 for shoes of a wide variety of styles, it being unnecessary in any case to use a greater number of molds than there are different sizes and widths of shoes to be made. In practice 35 fewer molds will be used than the actual number of sizes and widths of the filler pieces. For example, it has been found entirely practicable to make molds only for the full sizes and for the widths most commonly called for 40 and to produce the half sizes and widths less commonly demanded by trimming down filler pieces made from larger molds. In carrying out this idea, a set of from twelve to eighteen molds has proved to be sufficient to provide 45 satisfactorily for the entire range of variations in the sizes and widths of the filler pieces. By varying the shape of the patterns which serve as guides for the trimming of the foreparts of the filler pieces and trimming the 50 filler pieces in accordance with these patterns, the desired variations in style may be secured without the necessity of employing additional molds. Thus, to manufacture a line of filler 55 pieces comprising a complete range of sizes and widths and a predetermined number of different styles it is only necessary to employ a set of approximately eighteen molds and to provide appropriate patterns for use in trimming the filler pieces made by these molds, whereas if no subsequent trimming operations 60 are to be performed, a set of perhaps several hundred molds would be required to produce the same number of variations in size, width and style of filler pieces. The patterns are 65 preferably made of wood and may readily be

shaped by means of a jig saw. Thus it will be seen that the cost of making patterns of this character is very small compared to the cost of making molds. Obviously therefore the use of the patterns greatly reduces the cost of manufacturing the filler pieces. Furthermore, whenever it is desired to make changes in the styles of a line of filler pieces which are being manufactured, it is only necessary in accordance with the present invention to provide a new set of patterns shaped in accordance with the styles required. The making of a set of patterns is a very simple operation compared to the making of a set of molds and the patterns can be made much 75 more quickly than the molds. Consequently, a considerable saving of time may be effected.

Further objects and features of the invention will be apparent from the following description of the method contemplated by the 80 present invention and of the preferred means illustrated in the accompanying drawings for practicing said method.

In the drawings,

Fig. 1 is a view, in front elevation, of so 90 much of a sole rounding machine as is necessary to illustrate the application thereto of such devices as are preferably employed for effecting the trimming of the forepart of the 95 filler piece;

Fig. 2 is a perspective view showing a filler piece interposed between a pattern and a co-operating clamp which embody certain features of the present invention, and a rounding knife for trimming the forepart of the 100 filler piece;

Figs. 3 and 4 are plan views of the clamp and the pattern, respectively;

Fig. 5 is a plan view showing a filler piece before it has been trimmed to correspond to 105 the outline of a selected pattern;

Fig. 6 is a view, in vertical longitudinal section, of the clamp and the clamp carrier; and

Fig. 7 is a detail sectional view taken substantially along the line 7—7 of Fig. 6.

Referring first to Figs. 2 and 5 of the drawings, the filler piece 8 therein shown has been preliminarily formed so that the portion at the rear of the ball line (indicated at 10 in Fig. 5) has both the surface contour and marginal outline which is required for the finished product, while the forepart, or that portion of the filler piece which is forward of the ball line 10, is substantially flat and of such marginal contour as to allow for variations in the style of the filler piece, or, in other words, the forepart is made of such dimensions that its margin may be subsequently trimmed in accordance with patterns of different styles.

The trimming of the forepart of the filler piece is preferably accomplished by a rounding operation which may be performed by means of a rounding machine such as that illustrated in 130

part in Fig. 1, this machine being provided with certain parts especially constructed to locate and clamp the filler piece in position to be operated upon and to guide the rounding 5 knife so that it will operate only upon that portion of the filler piece which is forward of the ball line and thus will impart the desired marginal contour to the forepart without modifying in any degree the marginal 10 contour of the rest of the filler piece. The means for guiding the rounding knife consists of a pattern 12 which is horizontally disposed and serves to support the filler piece while it is being trimmed. The filler piece 15 is positioned longitudinally with respect to the pattern 12 in position to be operated upon by means of a pair of locating pins 14 which are provided at the rear of the pattern. After being located properly with respect 20 to the pattern 12, the forepart of the filler piece is securely held against the pattern by means of a clamp 16 carried by a clamp carrier 18 pivotally secured to the lower end of a slide 20 that is mounted for vertical reciprocation in an overhanging portion 22 of the machine frame. The slide 20 is connected to the forward end of an actuating lever (not shown) and is adapted to be actuated in the usual manner to cause the clamp 25 16 to be lowered into engagement with the work and to clamp the work against the pattern 12. A rounding knife is shown at 24 in Fig. 2, the knife being mounted upon a suitable knife carrier and actuated in the 30 usual manner to cause it to travel around the pattern.

The pattern 12 consists of a flat plate which may be of the shape best shown in Fig. 4. In this figure, a line 26 has been drawn transversely across the pattern at the rear of the forepart, this line bearing the same relation to the pattern as the ball line 10 bears to the 40 filler piece 8. The portion of the pattern 12 which is forward of the line 26 and which will hereinafter be referred to as the forepart of the pattern is necessarily somewhat smaller than the forepart of the filler piece for which it is designed to be used so that it may be superposed upon the filler piece and utilized 45 to guide the trimming knife. The margin of the pattern is shaped in accordance with the style of the toe and forepart of the shoe for which the filler piece is being made so that when the forepart of the filler piece 50 has been trimmed to conform to the pattern, it will then be adapted to fit properly within the shoe. At the rear of the line 26, the pattern is larger than the filler piece so that its margin will project beyond the edge of the 55 filler piece to hold the trimming knife out of engagement therewith and thus to prevent it from trimming this portion of the filler piece. The pattern functions to support the filler piece during the trimming operation and in 60 order that it may accomplish this purpose, it

is stationarily mounted upon two supporting posts 30 having reduced upper extremities adapted to enter apertures 32 (Fig. 4) in the pattern. The posts 30 may be rigidly mounted upon a frame or standard (not shown) 70 with provision for adjustment toward and from each other to adapt them to support patterns of different sizes.

It is desirable that the filler piece shall be located relatively to the pattern so that the 75 knife, as it travels around the edge of the pattern, will begin to trim the filler piece exactly at the point where the ball line intersects the margin at one side of the filler piece and will finish trimming exactly at the point 80 where the ball line intersects the margin at the other side of the filler piece. To facilitate locating the filler piece upon the pattern in this manner, the locating pins 14 are provided, these pins projecting perpendicularly from the face of the pattern at the heel end thereof and being located so as to engage the edge of the filler piece at opposite sides of a median line extending through the heel end thereof. The pins 14 are so located 85 as to position the filler piece longitudinally in proper position with respect to the pattern. The filler piece is to be located transversely with respect to the pattern by a manual operation, the operator using his fingers 90 to bring the edge portions of the filler piece at opposite ends of the ball line 10 into vertical alinement with the corresponding portions of the edge of the pattern at opposite ends of the line 26. When properly located 95 in the above-described manner, the filler piece will be so positioned with respect to the pattern that the trimming operation will commence at the point designated 34 in Fig. 5 and will terminate at the point designated 100 105 36 in said figure. The pattern is capable of being moved from the supporting posts 30 by merely lifting it to disengage the reduced upper ends of the posts from the apertures 32 in the pattern, after which the pattern 110 may then be reversed and replaced upon the supporting posts. The locating pins 14 extend through the pattern and project at either side thereof so that they are capable 115 of performing their locating function whichever side of the pattern is uppermost, portions of the pins at one side of the pattern serving to locate a filler piece for a right shoe, while the portions of the pins at the opposite side of the pattern serve to locate a filler piece 120 125 130 for a left shoe.

The clamp 16 which holds the filler piece against the pattern consists of a flat plate which corresponds in shape to that of the forepart of the pattern, but which is slightly smaller than said forepart so that its edge will not have to be accurately alined with the corresponding edge of the pattern. The clamp 16 is provided with a pair of holes 38 which are adapted to receive pins 40 which

project below a block 42 that is interposed between the clamp 16 and the clamp carrier 18 and is adjustably secured to the latter as will hereinafter appear. Clamps of various sizes and styles are provided to correspond with the sizes and styles of the patterns employed. The holes 38, however, are preferably spaced apart the same distance in the various sizes of clamps unless the clamps 10 are two small to permit of such an arrangement being made.

The clamp carrier 18 comprises a substantially rectangular hollow frame having elongated upper and lower horizontal walls 44 15 which are connected by short vertical walls 46 at the ends and at the rear side of the carrier frame. The front side of the carrier frame is open as shown at 48 in Fig. 7. Rising from the upper wall of the clamp carrier 20 is a vertical tongue 50 which is received in a transverse slot in the lower end of the slide 20. The clamp carrier 18 is pivoted to the slide 20 by means of a horizontal pin 52 which extends transversely through the tongue and 25 through the forked lower end of the slide 20. The clamp carrier 18 may be maintained in a fixed position relatively to the slide 20 upon which it is pivoted by any suitable means which will permit tilting adjustably of the 30 clamp carrier 18 and the clamp 42. As shown, a pair of pins 54 (Figs. 6 and 7) are supported in vertical sockets which are formed at opposite sides of the pivot pin 52 in the tongue 50 with the upper ends of the 35 pins engaging the top wall of the slot in the lower end of the slide 20. The lower cone-shaped ends of the pins 54 are engaged by similarly shaped ends of adjusting screws 56 which are disposed perpendicularly to the 40 pins 54 and are threaded into the clamp carrier frame from the rear side thereof. The screws 56 may be manipulated to release the carrier frame to permit tilting adjustment of the latter and to bind the carrier frame in 45 adjusted position.

The block 42 serves to space the clamp 16 from the clamp carrier 18 and is adjustably secured to the carrier 18 by means of a stud 58 and a nut 60, which centers the lower end of 50 the stud 58, is fixed in the block 42 and the upper portion of the stud extends through a horizontally elongated slot 62 in the lower wall of the clamp carrier frame and the nut 60 engages the upper face of said wall at opposite sides of the slot. The pin 40 extends 55 freely through a slot 64 in the block 42 and its upper portion extends freely through the slot 62 in the carrier frame. A collar 66 on the pin 40 is arranged to engage the lower face of the clamp carrier 18 at opposite sides of the slot 62 while a nut 68 at the upper extremity of the pin 40 engages above the lower wall of the clamp carrier, the collar 66 and nut 68 co-operating to clamp the pin 40 in adjusted position in the slot 62. A pin 70 ex-

tends transversely through the stud 40 and projects into the slot 62 to prevent the pin 40 from turning in the slot and thus to enable the nut 68 to be tightened to hold the stud 40 in adjusted position. The clamp 16 may be 70 adjusted lengthwise of the pattern 12 by loosening the nuts 60 and 68 and shifting the studs 58 and 40 in the slot 62. The stud 40 may be adjusted relatively to the stud 58 in the slot 62 to take up for wear in the holes 38 75 in the clamp 16 to insure that the clamp will be firmly gripped by the stud 40. This relative adjustment of the studs 40 enables them to be located closer together to adapt them for engagement with the holes 38 in small sized 80 clamps 16 in case it might be found desirable or necessary to locate said holes nearer each other than indicated in the drawings.

The filler piece is preferably built up from 85 separate sections of suitable sheet material such as impregnated felt, cork insoling, or the like. As heretofore stated, a main section may be employed which extends through the length and width of the filler piece and may be composed of one or more layers of sheet 90 material. A concave heel seat portion may be superposed over the heel end of the main section or interposed between the layers of said section. A balance piece may be associated with the shank and forepart of the 95 main section to correct the tendency of the foot to roll outwardly. The building up of the filler piece from separate sections in this manner does not constitute a part of the present invention and accordingly has not been 100 illustrated in the drawings. The filler piece blank thus produced is placed in a mold wherein it is shaped so that its lower side will conform to the surface contour of the interior of the shoe to which it is to be applied, while its upper face will conform to the foot of the wearer of the shoe. After being molded, the 105 filler pieces have the ultimately desired marginal and surface contour at the rear of the ball line, but forward of the ball line the dimensions and marginal contour of the filler piece are such as to make allowance for a wide 110 range of variations in style.

The molded filler piece is then ready to 115 have its forepart trimmed in accordance with the style of the forepart of the shoe in which it is to be inserted. In trimming the filler piece with the use of the pattern hereinbefore described, the filler piece is placed on the pattern with its margin at the rear of the heel portion in engagement with the pins 14, 14, these pins serving to locate the filler 120 longitudinally with respect to the pattern in position for the trimming operation. In placing the filler piece upon the pattern, the filler piece may conveniently be held between a finger and the thumb of one hand, the finger engaging the edge of the filler piece at one end of the ball line and the thumb engaging the edge at the opposite end of the ball line. 125 130

After the heel portion of the filler piece has been properly brought into engagement with the pins 14, the thumb and finger, by which the forepart of the filler piece is held, will 5 readily engage the opposite edges of the pattern and may be utilized to align the edge portions of the filler piece at opposite ends of the ball line with the corresponding edge portions of the pattern and thus transversely 10 to locate the forepart of the filler piece relatively to the pattern in position for the trimming operation.

The clamp 16 is then depressed into engagement with the filler piece to clamp the 15 latter against the pattern and will hold the filler piece securely while it is being trimmed. The trimming knife 24 is set in motion in a manner usual in sole rounding machines, the knife moving forwardly from the position 20 in which it is shown in Fig. 2 and being guided by the pattern. As the knife intersects the vertical plane of the ball line of the filler piece, it encounters a portion of the margin of the filler piece which projects 25 beyond the edge of the pattern and the knife then begins to trim off this projecting portion of the filler piece. The trimming continues around the forepart and toe of the filler piece until the knife reaches that portion 30 of the edge thereof which is adjacent to the opposite end of the ball line. At this point, the margin of the filler piece ceases to project outwardly beyond the edge of the pattern and when the trimming operation 35 has been finished, the forepart of the filler piece has been trimmed in accordance with the shape of the pattern. During the remainder of the rounding movement of the trimming knife, the knife rides idly along 40 the edge of the pattern until it reaches the point from which it started. The clamp 16 is then released and the completed filler piece is removed from the work.

Having thus described my invention, what 45 I claim as new and desire to secure by Letters Patent of the United States is:—

1. In a machine for operating upon filler pieces for shoes, a stock trimming device, means for supporting a filler piece and guiding 50 said device to enable the latter to trim a portion at one end only of the filler piece, and means for moving said device entirely around the filler piece.

2. In a machine for operating upon filler 55 pieces for shoes, a stock trimming device, and means for supporting a filler piece and relatively moving and guiding the filler piece and said device to cause the latter to trim the toe and forepart of the filler piece without 60 trimming any of the remaining portion of the filler piece.

3. In a machine for operating upon filler 65 pieces for shoes, a cutter, and means for supporting a filler piece and for moving and

guiding the cutter to trim the toe and fore- 65 part only of the filler piece.

4. In a machine for operating upon filler pieces for shoes, a cutter, and means for supporting a filler piece and for moving and guiding the cutter to trim that portion only 70 of the filler piece which is forward of the ball line.

5. In a device for operating upon filler pieces for shoes, a trimming knife, and means for relatively moving the knife and a 75 filler piece to cause the knife to trim the forepart of the filler piece without trimming any other portion thereof.

6. A device for operating upon filler pieces for shoes comprising a trimming knife, and 80 a pattern for supporting a filler piece and for guiding the knife to enable it to trim the margin of the filler piece forward of the ball line without trimming any other portion of the filler piece. 85

7. A device for operating upon filler pieces for shoes comprising a trimming knife, a pattern for supporting a filler piece and for guiding the knife to enable it to trim the margin of the filler piece forward of the 90 ball line without trimming any other portion of the filler piece, and means for operating the trimming knife.

8. In a device for operating upon filler pieces for shoes, a pattern adapted to engage 95 one face of a filler piece and to be positioned relatively thereto with the portion of the filler piece forward of the ball line projecting beyond the margin of the corresponding portion of the pattern and with the rest of the 100 pattern projecting beyond the portion of the filler piece at the rear of the ball line, and a trimming knife adapted to be moved around the pattern to trim the projecting portion of the filler piece. 105

9. In a machine for operating upon filler pieces for shoes, a pattern adapted to engage one face of a filler piece and to be positioned relatively thereto with the portion of the 110 filler piece forward of the ball line projecting beyond the margin of the corresponding portion of the pattern and with the rest of the pattern projecting beyond the portion of the filler piece at the rear of the ball line, means for locating the filler piece relatively to the pattern, a trimming knife, and means for moving the knife around the pattern to trim the projecting portion of the filler piece. 115

10. In a machine for operating upon filler pieces for shoes, a support for a filler piece, a cutter, means for moving the cutter around the filler piece, and means on the support for engaging and guiding the cutter to cause it to trim the forepart of the filler piece to a predetermined contour to prevent it from trimming the remaining portion thereof. 120

11. In a machine for operating upon filler pieces for shoes, a trimming knife having an 125

orbital path of movement, means for moving the knife, means for supporting the filler piece in the plane of movement of the knife and for guiding the knife to cause it to trim 5 the portion of the filler piece forward of the ball line and to prevent the knife from trimming the portion of the filler piece rearward of the ball line.

12. In a machine for operating upon filler 10 pieces for shoes, a trimming knife, a pattern having a marginal contour shaped to guide the trimming knife to enable it to trim the forepart of a filler piece and to prevent it from engaging the shank and heel portions of 15 the filler piece, means for holding the filler piece against the pattern, and means for moving the knife around the pattern to effect the trimming operation.

13. In a machine for operating upon filler 20 pieces having a molded surface contour rearward of the ball line, a flat forepart forward of the ball line, a pattern for supporting the filler piece and determining the marginal contour of the forepart, the pattern being shaped 25 to overlap the portion of the filler piece rearward of the ball line, a clamp for engaging only the forepart of the filler piece to hold it against the pattern, a trimming knife, and means for moving the knife around the pattern to trim the forepart of the filler piece.

14. In a machine for operating upon filler 30 pieces for shoes, a pattern having a forepart of the size and shape desired for that portion of a filler piece which is forward of the ball line, and having a rear part adapted to project outwardly beyond the filler piece throughout the length of its margin rearward of the ball line, and means for engaging the margin of the filler piece to locate the filler piece relatively to the pattern for the trimming 35 operation.

15. In a machine for operating upon filler 40 pieces for shoes, a pattern having a forepart of the size and shape desired for that portion of a filler piece which is forward of the ball line, and having a rear part adapted to project outwardly beyond the filler piece throughout the length of its margin rearward of the ball line, and projections on the pattern 45 for engaging the margin of the filler piece at the heel end thereof to locate the filler piece relatively to the pattern for the trimming operation.

16. In a machine for operating upon filler 50 pieces for shoes, a pattern having a forepart of the size and shape desired for that portion of a filler piece which is forward of the ball line, and having a rear part adapted to project outwardly beyond the filler piece throughout the length of its margin rearward of the ball line, means carried at each side of 55 the pattern for engaging the margin of the filler piece at the heel end thereof to locate the filler piece relatively to the pattern for the trimming 60 operation, means for support-

ing the pattern in horizontal position, detachable interengaging securing means on the pattern and the pattern supporting means constructed and arranged to permit the platform to be secured to the support with either 70 side uppermost to adapt it for use with filler pieces for right and left shoes, and a clamp for securing the filler piece to the pattern.

17. In a machine for operating upon filler 75 pieces for shoes, a pattern having a forepart of the size and shape desired for that portion of a filler piece which is forward of the ball line, and having a rear part adapted to project outwardly beyond the filler piece throughout the length of its margin rearward of the ball line, said pattern having a 80 hole extending therethrough at both forepart and heel end thereof, means for detachably and rigidly supporting the pattern with either side uppermost by engagement with 85 said holes, a pair of pins carried by the pattern for engaging the margin of the filler piece at the heel end thereof to locate the filler piece relatively to the pattern for the trimming operation, and a clamp for securing the 90 filler piece to the pattern, said pins extending through the pattern and projecting beyond each side thereof.

18. In a machine for operating upon filler 95 pieces for shoes, a trimming knife, a pattern having a marginal contour shaped to guide the trimming knife to enable it to trim the forepart of a filler piece and to prevent it from engaging the shank and heel portions of the filler piece, a clamp comprising a plate 100 shaped to engage the exposed face of the filler piece forward of the ball line only, and means for detachably supporting said clamp and for moving it into and out of clamping engagement with the filler piece.

19. For use in trimming filler pieces for 105 shoes, a pattern shaped to guide a cutter around the toe and forepart of a filler piece to trim the same and to hold the cutter away from the shank and heel of the filler piece 110 to prevent the shank and heel portions from being trimmed as the cutter travels around them.

20. For use in trimming filler pieces for 115 shoes, a pattern shaped to guide a cutter around the toe and forepart of a filler piece to trim the same and to hold the cutter away from the rest of the filler piece, said pattern having work-engaging means for relatively 120 locating the filler piece and pattern for the trimming operation.

21. For use in trimming filler pieces for 125 shoes, a pattern having its margin shaped at the forepart thereof to guide a knife around the forepart of a filler piece to trim the same, and having the remainder of its margin shaped to guide the trimming knife around the remainder of the filler piece without engaging the latter.

22. For use in trimming filler pieces for 130

shoes, a pattern having its forepart smaller and its rear part larger than the respective portions of a filler piece with which it is designed to be used whereby it will function to

5 guide a trimming knife around the filler piece in engagement with the forepart thereof to trim the same but out of engagement with the rear portion of the filler piece.

23. A device for use in trimming filler 10 pieces for shoes comprising a pattern shaped to guide a knife around the forepart of a filler piece and to prevent the knife from cutting around the rest of the filler piece, and 15 projections carried by the pattern for engaging the margin of the filler piece at the heel end thereof to locate the filler piece relatively to the pattern for the trimming operation.

24. For use in trimming filler pieces for 20 shoes, a pattern comprising a flat plate having a marginal edge shaped to determine the outline of the toe and forepart of a filler piece for a right shoe placed against one side of the pattern and of the corresponding portion 25 of a filler piece for a left shoe placed

against the opposite side of the pattern, and projections upon each side of the pattern for locating a filler piece relatively to the pattern in position to be trimmed.

25. For use in trimming filler pieces for 30 shoes, a pattern comprising a flat plate having a marginal edge shaped to determine the outline of the toe and forepart of a filler piece for a right shoe placed against one side of the pattern and of the corresponding portion of a 35 filler piece for a left shoe placed against the opposite side of the pattern, a pair of pins extending through the heel end of the pattern at opposite sides of the medial line thereof and projecting beyond one side face of the pattern to engage the margin at the heel end of a filler piece for a right shoe and beyond the opposite side face of the pattern to engage the margin at the heel end of a filler piece for a left shoe to locate said filler pieces 40 relatively to the pattern in position to be trimmed.

In testimony whereof I have signed my name to this specification.

GEORGE H. HEYS.
